UNITED STATES PATENT OFFICE

2,555,988

TOURIST CABINET STOOL

Rose H. Nelson, Sacramento, Calif.

Application August 12, 1946, Serial No. 689,969

1 Claim. (Cl. 312—235)

1

The present invention relates to a convertible baggage carrier of a type adapted for use by tourists, and more particularly pertains to a cabinet which may serve as a means for encasing wearing apparel and the like, and which may also be opened to serve as a dresser.

A more detailed object of the invention is to provide a slidable member in association with the cabinet, which may be withdrawn to an extended position and serve as a seat.

A still further object of the invention is to provide novel grasping means for manually withdrawing the slidable member from the cabinet assembly.

Other objects and features of the invention will be apparent upon consideration of the accompanying drawings and the following description wherein an exemplary embodiment of the invention is disclosed.

In the drawings:

Fig. 1 is a perspective view of the cabinet embodying the invention illustrating all of the parts in a closed position.

Fig. 2 is a transverse sectional view of the cabinet on the section line 2—2 in Fig. 1.

Fig. 3 is an end elevational view showing the seat in an extended and erected position.

Fig. 4 is a perspective view illustrating the manner in which the cabinet may serve as a dresser.

Fig. 5 is a fragmentary sectional view taken through the upper compartment on the line 5—5 of Fig. 4.

Fig. 6 is a bottom plan view of the folded seat assembly.

The invention relates to a tourist cabinet and seat combination which serves as a trunk within which various items of wearing apparel and the like may be stored during transit. The cabinet structural arrangement includes a slidable member which may be withdrawn from a position within the cabinet to serve as a seat. The top cover of the cabinet is hinged and provided with a mirror on the inner face whereby the device may serve as a dresser.

The cabinet is substantially rectangular in shape and may be formed of any suitable material such as metal, plastic or wood. The top portion of the cabinet is adapted to provide a relatively large compartment 10 within which hats, caps and the like may be stored. Immediately below the compartment 10 a cosmetic drawer 11 is provided which is adapted to be mounted in a conventional manner so as to slide outwardly and expose a plurality of com-

partments therein. This drawer carries a plurality of partitions (not shown) within which cosmetics, handkerchiefs, stockings, medicines and the like, may be arranged. The drawer 11 is provided with recessed hand grips, as illustrated, whereby the drawer may be withdrawn from a closed position. The drawer 11 is adapted to slide in suitably shaped grooves in the side walls as illustrated in Fig. 5. The compartment 10 is separated from the drawer 11 by a bottom member 4.

A plate-shaped slide member 12 is mounted below the drawer 11 and is adapted for sliding movement in the side walls of the cabinet as illustrated in Fig. 5. The slide member 12 is adapted to serve as a seat in the extended position, and for this purpose a plurality of legs 20 are provided. The legs 20 are connected at their upper ends by reinforcing bar 19, as shown in

Fig. 4, and the leg assembly is hinged to the underside of the member 12 by means of a plurality of hinges, one of which is shown at 9. The hinge structure is such that when the legs are unfolded from the horizontal position, the upper ends of the legs 20 and the reinforcing bar 19 will prevent further outward swinging of the legs and thereby provide an adequate support for the member 12, when it is used as a seat. The legs 20 may be folded to lie under the member 12 and the entire seat structure may then be pushed into the cabinet. It is for this purpose that the grooves in the side walls of the cabinet are large enough to accommodate both the plate member 12 and legs 20. The inner end of the seat portion 12 is provided with a cross bar 21 as shown in Fig. 6. This bar has a thickness substantially equal to the thickness of the legs 20. The bar 21 accordingly supports the inner end of the plate 12 when it is in extended position. The bar 21 is attached to the under side of the seat 12 and is spaced at 21a from the ends of the legs 20 when they are in folded position.

A further drawer 13 is provided below the seat member 12. The drawer 13 is adapted for accommodating lingerie, slips, and the like. The drawer 13 is mounted for sliding movement in suitably arranged grooves in the side walls of the cabinet. This drawer may be provided with a slot 8, whereby the drawer may be grasped and conveniently withdrawn from the closed position. This slot 8 also permits the finger tips to be introduced therethrough and engage a recessed hand grip 3 in the reinforcing bar 19. This recess 3 will be arranged under the seat 12

when the seat assembly is in a folded and closed position.

Another drawer 14 is mounted below the drawer 13, and this drawer is designed to accommodate shirts, underwear, pajamas, sweaters, and the like. The drawer 14 is provided with hand grips as illustrated in Figs. 1 and 4, whereby the drawer 14 may be manipulated to an open position.

The compartment 10 is closed by a hinged cover 15 which is adapted to swing to a substantially vertical position as shown in Fig. 4. The hinged cover 15 may be provided with a collapsible hand grip 6, as shown in Fig. 1. The cover 15 may be secured in closed position in any suitable manner. The hinged cover 15 carries a mirror 16 on the inner face thereof, of such dimensions as to substantially cover the inner face of the lid 15. The mirror 16 may be secured to the lid 15 by means of screws or the like. The mirror 16 is of such dimensions as to lie within the compartment 10 when the lid 15 is closed, whereby the mirror is protected during transit. The mirror is so arranged that when the hinged member 15 is in open position, the mirror will serve as a reflecting surface for the head and shoulder portions of a person seated on the member 12.

The upper compartment 10 is provided with a plurality of bags 17, which may be formed of any suitable flexible material attached to the side walls of the cabinet. The bags 17 are adapted to receive hair nets, head wrappings, gloves, and the like, or any articles of clothing which may be readily folded without the disadvantages of irregular creasing. The rear wall of the compartment 10 is provided with a plurality of resilient straps 18 which may be attached to the rear wall in any suitable manner. The straps 18 may be formed of rubber tape or the like. The straps 18 will then serve to retain various items required during travelling, along the rear wall of the chamber 10.

While the invention has been shown and described with reference to specific structural de- 45

tails, it will be appreciated that various changes may be made in the cabinet structure. Various modifications may be made without departing from the spirit and scope of the invention as set forth in the appended claim.

I claim:

A cabinet assembly comprising, two spaced side walls, a rear wall joining said side walls, a front wall joining said side walls, said side walls 10 each having a groove therein, a plate member 15 slidable in the grooves of said side walls and withdrawable from a position within the cabinet, a pair of legs, a reinforcing bar connecting end portions of said legs, hinges pivotally connecting 20 the legs to an underside of said plate member whereby the legs and the bar may be hinged to lie along the under face of the plate member, said grooves in the sidewalls having a vertical dimension slightly greater than combined thickness of said plate member and one of said legs so that said grooves slidably accommodate said legs, said reinforcing bar having a slot in the outer face thereof, a drawer mounted for sliding movement on the side walls below said plate 25 member, a front closure-forming panel of said drawer having a slot extending into its upper edge in alignment with the slot in said reinforcing bar.
